UNITED STATES PATENT OFFICE.

DANIEL B. BRYAN, DECEASED, LATE OF LEXINGTON, KENTUCKY, BY MARY B. BRYAN,
ADMINISTRATRIX, OF LEXINGTON, KENTUCKY, ASSIGNOR TO THE PATENT APPLI-
ANCE CO., OF NEW YORK, N. Y., A CORPORATION OF NEW YORK.

SLIDING DOOR.

1,163,065.

Specification of Letters Patent.

Patented Dec. 7, 1915.

Application filed June 15, 1914. Serial No. 845,114.

To all whom it may concern:

Be it known that I, MARY B. BRYAN, a citizen of the United States, and a resident of Lexington, county of Fayette, and State of Kentucky, make this application as administratrix of the estate of DANIEL B. BRYAN, deceased, late a citizen of the United States and a resident of said Lexington, Fayette county, Kentucky, and that said DANIEL B. BRYAN, deceased, invented certain new and useful Improvements in Sliding Doors, of which the following is a specification.

The invention referred to relates to improvements in doors of the type in which a door or door section is mounted in a substantially vertical plane, in its closed position, covering the door-opening, and upon opening is swung upwardly and inwardly into an approximately horizontal plane above the door-opening, and to means for operating such doors. Doors of this character are particularly adapted for use in factories, freight sheds and the like, where large doorway openings and large heavy doors are often required. In such doors the opening movement comprises a lift in a vertical direction and a swinging movement from the vertical into the final horizontal position.

The object of the present invention is to provide devices calculated to facilitate the change in direction during the opening of the door, from the vertical rise, or movement in one direction, to the swinging movement into a horizontal, or different plane from that in which the doorway opening is situated.

A door of the type to which the present improvement is adapted to be applied is described in patent to Schwemlein, 1,069,733, dated August 12, 1913, although the present invention is not limited in its usefulness to doors of the particular description referred to. Such doors comprise two or more sliding panels or sections, the lower section or sections being first raised, in opening, into guideways formed on the face of the upper section, after which a continuance of the lifting movement results in a swinging of the nested sections about a sliding or rolling pivot, which movement is controlled by links pivoted to the top door section and the fixed frame of the doorway. If, in such a struc-

ture, the supporting links make only a slight angle to the vertical, when the door is in closed position, a considerable effort may be required to start the door in its swinging movement away from the vertical, since the lifting force is exerted in a vertical direction. The present invention overcomes this difficulty by providing devices whereby the top of the door is pressed away from the vertical plane at the moment when the inward swinging movement of the door is to begin.

In the embodiment of the invention which is considered particularly effective these devices take the form of bell-crank levers pivoted on the top section of the door, which levers are caused to exert a leverage against the wall or fixed member adjacent the opening, when the arms of the levers are contacted by members moving upwardly with a lower section of the door, to start the inward movement of the top of the door away from the vertical plane.

In order that the invention may be more clearly understood, attention is hereby directed to the accompanying drawings, illustrating certain embodiments of the invention.

In the drawings, Figure 1 is a front view of a three-section door equipped with the present improvements, the door being in closed position; Fig. 2 is a vertical section through the door with the sections thereof in closed position; Fig. 3 is a partial vertical section similar to Fig. 2, in which the swinging movement of the door has begun, and Fig. 4 is a similar partial vertical section with the nested door sections moved into horizontal position above the doorway.

Referring to the drawings, the door illustrated is provided with lower, intermediate and top sections 1, 2, and 3 respectively, it being understood that the invention is equally applicable to a two-section door. Section 1 is slidably mounted in vertical fixed guideways 4, and section 2 in parallel fixed guideways 5. The top section 3 is secured within or its formed integral with a frame or carrier 6, which is provided with guideways 7 and 8, which, in the normal or closed position of the carrier shown in Fig. 2, are in alinement with the guideways 5 and 4 on the door frame. This construction permits the sections 1 and 2 to be moved

into the alining guideways 8 and 7 of the carrier, on the door section 3, after which the carrier with the three sections contained therein is swung into the horizontal position shown in Fig. 4, the arrangement being such that a continuance of the lifting movement which carries the lower sections into the carriers, swings the carrier, together with the upper and lower door sections, about a pivotal point.

In the construction illustrated, the carrier 6 is provided near its lower edge with rollers 9, which travel on vertical tracks or surfaces 10. The carrier is supported by links 11, which are pivotally mounted on pins 12 carried by brackets 13 secured to the wall 14 above the doorway. The links are pivoted to the carrier at 15, usually in line with the innermost carrier-guideway 8, and above the middle of the carrier. The carrier, in the form of door illustrated has a rigid member 16, usually an I-beam or other structural shape, extending across the top of the carrier and constituting an abutment against which the lower door-sections strike when raised fully into the carrier.

In the door illustrated, the construction is such that the turning of hand crank 16, at one side of the door frame, raises door-sections 1 and 2 into their guides 8 and 7 in alinement with section 3, after which continued movement of crank 16 results in the swinging movement of the carrier with all three door-sections nested therein, as stated. A sprocket wheel 17 is mounted on the shaft of the hand crank and sprocket chain 18 passes around this wheel and around a sprocket wheel 19 on a shaft 20 carried by a bracket 21 at the upper end of the door frame, above the hand crank, as shown in Fig. 1. A gear 22 on the shaft 20 meshes with gear 23 on a shaft 24 also carried by bracket 21. Sprocket wheels 25 and 26 on shaft 24 carry sprocket chains 27 and 28, the former extending downwardly along the right side of the door frame and attached to the bottom door-section by means of a bracket 29, and the latter extending across the top of the frame, around a guide pulley 50 or sprocket 30, and down the left side of the frame to a connection with the bottom door-section by means of bracket 31. The other ends of chains 27 and 28 are connected to a counterweight 32 at the right side of the door frame.

In the construction illustrated, the door-sections are connected for operation as follows:—Chains 33 are secured to the top corners of bottom section 1, pass around rollers 34 at the bottom of section 2, and are secured to the lower corners of section 3. The bottom section being raised by operation of the hand crank, section 2 will rise at half the speed of bottom section 1, and the two sections will simultaneously arrive

in parallel relation to section 3, in their guides in the carrier. If a two-section door is employed instead of a three-section door as shown, the means for lifting the intermediate section just described are, of course, not needed.

When the bottom section or sections have arrived in the carrier, on opening the door, they contact abutments such as the member 16 at the top of the carrier, so that the continuation of the lifting pressure is exerted upon the carrier itself. It is at this point that the specific improvements of the present invention come into play. These devices, in the construction illustrated, are as follows:—Bell-crank levers 35 are pivoted on studs 36 carried by brackets 37 mounted on the top of carrier 6 adjacent the side edges of the same and adjacent the front, or that edge of the door nearest to the door frame. The bell-cranks have arms 38, which in the closed position of the door extend vertically from their pivots, adjacent to the surface of the wall or frame 14, and arms 39 which, under the same conditions, lie horizontally upon the top of top plate 16 of the carrier. Brackets 40 mounted on the top of bottom door-section 1 adjacent the two side edges carry rollers 41, vertically in line with the horizontal arms of the bell-crank levers 35. When the bottom and intermediate door-sections are raised, brackets 40 and rollers 41 pass through openings in plate 16 of the carrier, rollers 41 coming in contact with the under sides of arms 39 of the bell-cranks. This contact occurs shortly before door-section 1 reaches its highest position in the carrier, and results in oscillating the bell-cranks about their pivots. Since arms 38 of the bell-cranks are in contact with, or lie closely adjacent to, wall 14, or preferably, plates secured to the wall, such as plates 10 on which rollers 9 run, as illustrated, the result of the tilting of the bell-cranks is to force the upper end of carrier 6 away from the wall, the upper ends of arms 38 of the bell-cranks pressing against plates 10 on the wall, and forcing the top of the carrier inwardly by the reaction of arms 38 against the pivots of the bell-cranks. During this operation the carrier tilts about rollers 9, the angle which links 11 make with the vertical becoming greater as the top of the carrier moves farther from the wall. When sections 1 and 2 have moved fully into the carrier, and abutted against plate 16, as shown in Fig. 3, the continued lifting movement of the hand chains raises the carrier as a whole, rollers 9 running on plates 10, and the upper end of the carrier moving inwardly in a curve under the control of links 11. The final position of the carrier is horizontal, as illustrated in Fig. 4, above the opening, with the lower end of the carrier in contact with plates 10 or wall 14, and

links 11 supporting the carrier in position. When the door is lowered, the reverse operations are gone through, the carrier coming into the position of Fig. 3 and then into 5 parallel relation with the door frame, door-sections 1 and 2 sliding back into their guides on the door frame.

It should be understood that the above description is illustrative merely, and that the 10 invention described herein is in no way limited to the particular type of door construction described, and that a two-section door, for example, may be used in place of a three-section door.

15 It is not at all essential to the present invention that the door-sections be raised in the manner described, or that the carrier be mounted and operated in the precise manner described. Neither is it essential that 20 the bell-cranks or equivalent mechanism be operated by the direct contact of members mounted on the top of a bottom door-section. What is essential to the invention is the provision of means on a door-member, which 25 member is so hung as to have a tendency to lie closely over an opening, which means are pressed against the wall, by contact of a moving member therewith, or otherwise caused to react against the door-member, 30 when lifting pressure is exerted on the latter, to cause the door member to move inwardly, or away from the plane of the opening, at the appropriate time.

Having now described the invention, what 35 I claim as new and desire to protect by Letters Patent, is as follows:

1. The combination of a door frame, a door adapted to be hoisted and lowered for 40 opening and closing the door opening, suspension means normally holding the door in position covering the opening, means for moving the door to open position, a movable member, and means moved by the door as the latter rises in opening into actuating 45 contact with said movable member to force an edge of the door away from the door frame, substantially as set forth.

2. The combination of a door frame, a door adapted to be hoisted and lowered for 50 opening and closing the door opening, suspension means connected to the door and the door frame in such manner as to give the door top a tendency to swing the door closed and to guide the top of the door, 55 when opened, away from the opening, means for hoisting the door to open position, and a movable member actuated by the door in its opening movement for imparting an initial opening movement to the door top, away from the opening, substantially as set forth.

3. The combination of a door-frame, a door adapted to be hoisted and lowered for 60 opening and closing the door opening, suspension means normally holding the door in position covering the opening, means for lift-

ing the door to open position, means on the door adapted to be pressed against the frame, and guided means actuated by said lifting means into contact with said means on the door for forcing the same against 70 the frame and thereby giving said door an initial movement away from the opening, substantially as set forth.

4. The combination of a door frame, a door adapted to be hoisted and lowered for 75 opening and closing the door opening, suspension means connected to the door and the door frame in such manner as to normally hold the door in position covering the opening, a lever pivotally mounted on the top 80 of the door, and means for operating said lever to give an initial opening movement to the door at the top, substantially as set forth.

5. The combination of a door frame, a door comprising an upper and a lower section and adapted to be hoisted for opening 85 and lowered for closing the door opening, means for suspending the door so that the door top has a tendency to swing closed, means for hoisting the door, and means operated by the lower section in its upward movement for imparting an initial opening movement to the top of the door in a direction away from the plane of the doorway opening, substantially as set forth. 90

6. The combination of a door frame, a door comprising a member adapted to be moved, in opening the same, first in the plane of the doorway opening, and then away from the same, means for raising the door, means 100 for causing the door member to move, after its movement in the plane of the opening, away from the said plane, and means mounted upon the door and actuated by the means for raising the door, to aid the initial movement of the door member away from the plane of the doorway opening, substantially 105 as set forth.

7. The combination of a door frame, a door comprising an upper section and a lower 110 section mounted to overlap the upper section in opening, suspension links pivotally connected to corresponding intermediate points in the edges of the top section, and to the door frame, and so positioned as to give the door top a tendency to swing closed, and to guide the door top away from the door frame in opening, and means upon the top and bottom sections caused to coact by the 115 upward movement of the lower section for 120 imparting an initial opening movement to the door top, substantially as set forth.

8. The combination of a door frame, a door adapted to be moved, in opening the same, away from the plane of the doorway 125 opening, means for opening the door, suspension links for suspending the door in closed position and for guiding its movement away from the doorway opening, means mounted on the door and adapted to 130

press against the frame, on actuation, to move the door away from the plane of the doorway opening, and means actuated by the door-opening means into operative relation to said means mounted on the door, and caused to operate the same, substantially as set forth.

9. The combination of a door frame, a door comprising an upper section and a lower section mounted to overlap the upper section in opening, suspension links pivotally connected to corresponding intermediate points in the edges of the top section, and to the door frame, and so positioned as to give the door top a tendency to swing closed, a pivoted bell-crank lever secured to the top of the upper section, having one arm adapted to press against the door frame, and means actuated by the upward movement of the lower section for oscillating said bell-crank for imparting an initial opening movement to the door top, substantially as set forth.

10. The combination of a door frame, a door comprising an upper section and a lower section mounted to overlap the upper section in opening, suspension links pivotally connected to corresponding intermediate points in the edges of the top section, and to the door frame, and so positioned as to

a pivoted bell-crank lever secured to the top of the upper section, having one arm adapted to press against the door frame, and one arm horizontally disposed, and means carried by the lower section adapted to contact 35 said horizontal arm, upon the rise of said lower section, to force the top of the door away from the plane of the doorway opening, substantially as set forth.

11. The combination of a door frame, a 40 door adapted to be raised and swung away from said door frame, suspension means normally holding the door in position to cover the opening formed by said frame, means for raising the door, a bell-crank lever pivot- 45 ed to the door, and means moved by said door-raising means into actuating contact with one arm of said bell-crank lever to press the other arm of said lever against the door frame to thereby force the part of the 50 door to which said lever is pivoted, away from the door frame, substantially as set forth.

This specification signed and witnessed this 29th day of May, 1914.

MARY B. BRYAN,
Admxx. of estate of Daniel B. Bryan.
